UNITED STATES PATENT OFFICE.

EDWARD STEWART, OF BATTLE CREEK, ASSIGNOR OF ONE-HALF TO
RICHARD W. LONSBERRY, OF RICHLAND, MICHIGAN.

BALANCED VALVE.

SPECIFICATION forming part of Letters Patent No. 278,058, dated May 22, 1883.

Application filed January 26, 1883. (No model.)

To all whom it may concern:

Be it known that I, EDWARD STEWART, a citizen of the United States, residing at Battle Creek, county of Calhoun, State of Michigan, have invented a new and useful Balance-Valve, of which the following is a specification.

The object of my invention consists in an improved construction to prevent the valve in a steam-chest from becoming set to its seat, and also to prevent an undue friction of said parts, caused by the pressure of the steam on the valve.

A further object is to construct a device for lubricating my improved valve.

In the drawings forming a part of this specification, Figure 1 shows a side elevation of the improved valve located in a steam-chest in section; Fig. 2, a perspective view of the valve and its lower bearing or seat, and Fig. 3 a broken portion of the valve enlarged.

m m illustrate the end walls of a rectangular steam-chest, and *y* the top wall.

C is a broken section of a cylinder.

P P are the steam-supply ports, and *T* the exhaust-port.

a a' show a style of valve commonly used, adapted for opening and closing alternately the mouths of the ports *P P*. In Fig. 1 a rim, *d*, with a valve-rod connected, is shown. Such valves are liable to become set to the seat or bearing-surface beneath, owing to the pressure of steam upon said valve.

B is a plate corresponding in size to the base-plate *a* of the valve below. Plate *B* has recesses *e e* in the corners, in which the heads of posts *r r* are located, said posts being secured in plate *a* below. The recesses *e e* are made a little deeper than the thickness of the heads of the posts *r r*, to admit of a rise and fall of plate *B*. The height of the posts *r r*, their heads, and the recesses *e e*, are so proportioned that there is a little space between plate *B* and wall *y* when said plate is at its lowest position, Fig. 3. Nuts *n* may be located on a threaded portion of the posts *r r*, as

illustrated, to regulate the degree of the play of plate *B*, by turning said nuts up or down, thus providing for the expansion of the metal of which the parts are composed. The plate *B* is forced against wall *y* by the sudden advent of steam through the ports, and is held in said position by the force and volume of steam between said plate and the lower valve, *a a'*. When the plate *B* is in this position the shoulders of the post-heads rest against the lower wall of recesses *e e*. Thus the steam exerts as great a pressure on plate *B* as on plate *a*, and said pressures, acting against each other, and being limited, and both plates having a bearing-surface during the movement of the valve, said valve is prevented from becoming set, and undue friction of bearing-surfaces of said parts is obviated. In order to lubricate both plate *B* and the seat or bearing-surface of plate *a* and the ports *P P*, I provide an oil-cup having an upward-extending center tube with a perforation leading into the steam-chest, and pipes *t t*, leading from each side into the steam-chest in a position to deposit oil near the mouth of the ports *P P*, Fig. 1.

Having thus described my invention, what I claim is—

1. In a balance-valve, the combination of the plate provided with the corner recesses, the slide-valve and its plate, and the headed posts connecting said parts, substantially as set forth.

2. The combination of the valve provided with the headed posts, the adjusting-nuts, and the plate having the corner recesses, substantially as described.

3. The combination, with the balance-valve having the two bearing-surfaces, of an oil-cup having the perforated tube and side pipes adapted to carry oil to both bearing-surfaces, substantially as set forth.

EDWARD STEWART.
